UNITED STATES PATENT OFFICE.

ANNA HELD ROBERTS, OF HAMDEN, CONNECTICUT, ASSIGNOR TO STROUSE ADLER & CO., A FIRM COMPOSED OF ISAAC M. ULLMAN, LOUIS M. ULLMAN, AND GEORGE MEYER, OF NEW HAVEN, CONNECTICUT.

EVENING-DRESS BODICETTE.

Application filed July 17, 1926. Serial No. 123,127.

Fig. 1 is a view showing a development of my improved bodicette; and

Fig. 2 is a view on a smaller scale of the same in rear elevation, showing the open-back brassière thereof.

My invention relates to an improvement in that class of garments for women's wear known as "bodicettes," which combine, in one garment, a girdle and a brassière, the object of my present invention being to produce a bodicette designed with particular reference to being worn with evening dress and to giving the wearer a high degree of ease and comfort, insofar as the garment provides for ventilation and exceptional freedom of movement.

With these ends in view, my invention consists in a bodicette characterized by having a girdle-portion and an open-back brassière.

My invention further consists in a bodicette characterized as above and having certain other details of construction as will be hereinafter described and particularly pointed out in the claims.

In carrying out my invention, as herein shown, the girdle, which is fashioned to extend from the waist-line down well over the hips, comprises a non-elastic front 5 and a non-elastic back 6, the upper or abdominal portion of the former being reinforced as shown by a medial bone 7, and two outwardly-inclined bones 8 located on the opposite sides thereof, and the back-portion 6 being reinforced by five vertically-arranged, substantially-parallel bones 9, of which the two outer bones, located at its edges, are somewhat shorter than the three intermediate bones.

The right-hand side-section of the girdle comprises a non-elastic, hip-covering section 10 extending from the upper to the lower edge of the girdle and arranged to cover the right hip of the wearer, this section being reinforced at its upper ends by short bones 11. Between the said non-elastic hip-covering section 10 and the non-elastic front-section 5, I locate an elastic-section 12 extending from the lower to the upper edge of the girdle and tapering from its lower to its upper end. Between the opposite edge of the said non-elastic section 10 and the adjacent or forward edge of the non-elastic back-section 6, I locate an elastic

gore 13 of about half the depth of the girdle and cut on a bias at its upper end and merging thereat into a non-elastic gore 14, from which it is separated by a seam or overlap 15.

The left-hand side-section of the girdle is made in the same manner as the right-hand side-section thereof, and comprises the same elements, which are designated by corresponding numerals, save that the non-elastic hip-covering section corresponding to the hip-section 10 before described, is longitudinally divided to form half-sections 10¹—10², furnished upon their respective edges with individual fastening devices in the form of eyes 16 and hooks 17, these fastening devices, as will be noted, being located directly in non-elastic portions of the garment and well separated from the elastic portions thereof.

It will also be particularly noted that those portions of the girdle which overlie the hips proper of the wearer are non-elastic, the elastic elements 12 and 13 of the girdle being located between these non-elastic, centrally-arranged hip-covering sections 10 and the non-elastic front and back-sections 5 and 6 of the girdle.

The brassière feature of my improved bodicette has its front composed of a central section 18 and complementary side-sections 19, the former consisting of an upward extension of the non-elastic front-section 5 of the girdle, and the latter being made independent of and applied to the upper ends of the elastic and non-elastic elements of the side-sections thereof, but in no case do the elastic elements of the girdle extend upward into the brassière thereof.

The described brassière is supported at its respective ends by two complementary, substantially-triangular brassière-supports 20 having downwardly- and rearwardly-curved upper edges continuing the curve of the bowed upper edge of the brassière. The said supports, virtually forming upward extensions of the non-elastic hip-sections 10 and the non-elastic gores 14, are each reinforced by two diagonally-arranged bones 21 differentiated in length according to their position. The upper edge of the back-section 6 of the girdle is provided with a horizontally-arranged elastic strap 22 extending entirely across it and joining the rear edges

of the said brassière-supports 20, which are thus connected with the non-elastic back-section 6 of the girdle and held down in place upon the back of the wearer. Inasmuch as 5 the back-section of the girdle is but little higher than the front-section thereof, my improved bodicette leaves the back of the wearer exposed to the extent required by full evening dress.

10 By the construction just described, I am enabled to make the brassière open at the back to the depth of the upper edge of the back-section 5 of the girdle and still adequately support the front portion of the 15 brassière.

In this way I secure an open-back brassière adapting the bodicette to be worn with evening dress and securing exceptional freedom and ease to the wearer, as well as 20 the coolness proceeding from having the brassière entirely open at the back.

As shown, the front-section 18 of the brassière is furnished with a V-shaped insert 24 of lace, enhancing the appearance of the 25 garment and also making it cool to wear. Shoulder straps 25 extend between the section 20 of the brassière and the elastic band 22 already mentioned, and assist in supporting the brassière.

30 I claim:

1. An evening-dress bodicette, combining a girdle and a brassière, the girdle comprising a non-elastic front-section, a non-elastic back-section, and two complementary side-

sections combining elastic and non-elastic 35 elements; a brassière located at the upper edge of the front-section and the forward portions of the upper edges of the two side-sections; brassière-supports located at the upper ends of the rear portions of the side-sections, and a horizontally-arranged elastic band located at the upper edge of the back-section and at its ends co-acting with the rear extremities of the said brassière-supports for holding the same flat upon the back 45 of the wearer of the bodicette.

2. An evening-dress bodicette, combining a girdle and a brassière, the girdle comprising a non-elastic front-section, a non-elastic back-section, and two complementary side-sections each having a non-elastic hip-covering section and elastic sections located on either side of the same; a brassière rising from the upper edge of the said non-elastic front-section and from the adjacent portions 50 of the said side-sections and having a bowed upper edge; brassière-supports connected with the respective ends of the said brassière, and a horizontally-arranged elastic band located at the upper end of the said back-section and extending between and connecting the rear-end portions of the said brassière-supports, which are thus held down upon the back of the wearer.

55 In testimony whereof, I have signed this 65 specification.

ANNA HELD ROBERTS.
